BUCKLE CONSTRUCTION

Jacob S. Feiner, Bronx, N. Y.

Application March 1, 1949, Serial No. 78,911

4 Claims. (Cl. 24—178)

1

This invention relates to a buckle construction.

It is an object of the present invention to provide a buckle construction adapted for use on wrist watch straps and belts wherein the free end of the strap can slide through the buckle construction without the free end of the strap having to be bent and to preserve the leather of the strap, increase its life, keep its stitches from being opened and the leather surface from being marred.

It is another object of the invention to provide a buckle construction adapted for use with an enlarged or thickened free end of the strap wherein the free end of the strap cannot leave the buckle and thereby to provide a safety watch strap which will prevent the watch from being dropped while the watch is being put on or taken off the wrist of the wearer and wherein it is unnecessary for the wearer to hold the watch close to the body while loosening the strap or tightening the same about the wrist.

Other objects of the present invention are to provide a buckle construction which permits the easy sliding movement of the free end of the strap through the same, which is of simple construction, inexpensive to manufacture, easy to assemble upon the strap, has a minimum number of parts, sturdy and rugged, convenient to use and efficient in operation.

For other objects and for a better understanding of the invention, reference may be had to the following detailed description taken in connection with the accompanying drawing, in which

Fig. 1 is a perspective view of a wrist watch having the buckle construction according to one form of the invention connected to its strap and illustrating the manner in which the strap is fixed about the wrist of a wearer.

Fig. 2 is a perspective view of the buckle construction shown in Fig. 1.

Fig. 3 is a longitudinal sectional view of the buckle and strap portions shown in Fig. 2 and as viewed on line 3—3 thereof.

Fig. 4 is an enlarged sectional view taken on line 4—4 of Fig. 3.

Fig. 5 is a perspective view of a modified form of the invention wherein the tongue is pivoted on the same part which the pivoted slide is connected.

Fig. 6 is a perspective view of a still further form of the invention without the pivotal slide, but having a groove for receiving the tongue and the safety strap feature.

Fig. 7 is a perspective view of a still further

2

form of the invention and of a buckle construction adapted for use with a large belt.

Fig. 8 is a fragmentary view of one end of the buckle showing the pivoted slide and the groove therein for receiving the tongue.

Fig. 9 is a longitudinal sectional view taken on line 9—9 of Fig. 7.

Referring now particularly to Figs. 1 to 4, 15 represents a wrist watch to which straps 16 and 17 are connected. The strap 16 is of double thickness and is folded at its end, as indicated at 18, and stitched along the sides, as indicated at 19, to retain a pin 21 projecting from the opposite sides of the strap and on which is pivoted a slide or U-shaped member 22 having depending side portions 23 receiving the ends of the pin 21. This slide 22 can pivot and through the same may be extended the strap 17 having holes 24 for receiving a bent tongue 25.

20 The tongue 25 is secured to the strap by a pin 26, Fig. 4, embedded in the strap 16 and held against longitudinal displacement by the stitchings 19 and against displacement within the strap by stitchings 27, Fig. 3. The tongue 25 has an eye portion 28 receiving the pin 26. The strap has an opening 29 for receiving this eye portion 28 of the tongue 25.

25 The free end of the tongue is adapted to fit in a top groove or recess 31 in the pivotable slide 22 to hold the tongue against lateral displacement. In the free end of the strap 17 is an insert 32 which thickens that end of the strap so that it cannot pass through the slide 22. Accordingly, when the wrist watch is being placed on the wrist 35 of the wearer, the wearer need not be concerned about the same dropping from the wrist as the thickened end of the strap 17 will not pass through the slide 22 and accordingly, the watch cannot fall from the wrist. Because the slide can pivot, it can adapt itself to the strap 17 so that there is no need to bend the strap 17 to any appreciable amount to effect the sliding movement of the slide thereupon. The slide 22 moves along the strap 17 freely and easily and without the strap 17 having to be bent, distorted or worn.

30 The wearer need only grasp the thickened free end of the strap 17 and pull slightly with a little lifting movement and the slide will move easily and automatically into alignment with one of the openings 24 so that the tongue 25 can be easily and quickly inserted to finally fix the straps 16 and 17 together and to secure the watch upon the wrist.

35 In Fig. 5, there is a slightly different construction wherein the buckle comprises a U-shaped

member 34 having a transverse portion 35 which is retained in the folded over end of strap 16 and on which is pivoted tongue 36 adapted to enter the openings of strap 17 and to lie on pivot slide 37 having depending side portions 38 which are secured to the ends of the legs of the U-shaped member 34 by a through pin 39. This strap 17 extends through the slide and is retained therein by the pin 39. The space between the bottom face of the slide 37 and the pin is sufficient to receive the strap 17 but will not permit the enlarged end of the strap with the insert 32 from leaving the slide and accordingly, there is provided in this manner the safety feature for the watch. The operation of the buckle is the same as with the form of the invention above described. The slide moves freely upon the strap 17 by the mere grasping of the end of the strap 17 and with a slight lifting movement causing the slide to move inwardly toward the wrist for securement of the tongue 36.

In Fig. 6, there is shown a construction wherein the safety feature is made possible without the pivoted slide. The buckle has a main top portion 41 with depending and rearwardly extending side portions 42 to which the strap 16 is secured by a pin 43. A tongue 44 is pivoted on the pin 43 and its free end is adapted to enter a top recess 45 on the member 41. In this manner, the tongue is held against lateral displacement when extended through an opening 24 of the strap 17.

In order to keep control of the strap 17 by its enlarged end which has the insert 32, a rod or roller 46 extends between the side portions 42 immediately below the top thereof, the spacing being such as to permit free movement of the strap 17 therethrough except for the thickened end of the same containing the insert 32.

Referring now particularly to Figs. 7, 8 and 9, there is shown a still further form of the invention wherein the pivoted slide forms a part of a buckle adapted for use with heavy belts or straps. This buckle includes a U-shaped member 51 having a transverse portion 52 to which one end of the belt is attached and to which a long tongue 53 is connected for pivotal adjustment with respect thereto.

On the free ends of the U-shaped member 51 there is pivotally connected by pins 54, a pivotable slide member 55. This member has depending side portions 56 receiving the pivot pins 54. The slide 55 has a recess 57 in its top face for receiving the end of the tongue 53. The slide can be pivoted from a position shown in Fig. 8 to a position shown in Fig. 9, but its pivotal movement away from the tongue 53 is limited by flattened end surfaces 58 on the ends of the U-shaped member. The slide 55 has a notch 59 at the end of the recess 57 to keep control of the tongue when the slide 55 is pivoted to the position shown in Fig. 9.

It should be apparent that the slide 55 will pivot relative to the U-shaped member 51 to accommodate the free end of the belt through the buckle. There is no necessity for the free end of the belt to be distorted or worn while being passed through the buckle. The free end of the belt can remain substantially straight while the slide or the buckle glides thereover. When the buckle is in the proper location on the free end of the belt, it can be made fixed by the tongue 53 being extended through any one of a series of openings which are provided in the belt.

The notch 59 maintains control of the tongue

53 and will center and guide the free end of the tongue into place and into the recess 57. The tongue has its free end raised above the main portion of the same and its vertical part thereof 15 will enter the notch 59 so as to lie flush with the rear edge of the slide 55 whereby the vertical part of the free end as well as the horizontal part thereof will be thoroughly maintained within the recess 57 and the notch 59. Since the tongue 20 is extended through the openings of the belt or strap, the horizontal part of the free end of the tongue will be about all that will bear on the top face of the slide. The vertical part of the free end of the tongue passes through the opening. The horizontal part of the free end of the tongue 25 will accordingly be confined within the notch and recess so as not to interfere with other pieces of clothing or to provide an obstruction on which anything may become caught or torn. With the vertical part of the free end of the tongue lying flush with the edge of the slide, a more decorative appearance is given to the front face of the slide. The tongue part will appear to have the same width as the slide. The vertical part of the free end of the tongue engaging with the edge of the slide within the notch 59 provides a stop to limit the rearward pivotal movement of the slide.

While various changes may be made in the detail construction, it shall be understood that such changes shall be within the spirit and scope of the present invention as defined by the appended claims.

What is claimed is:

35 1. A buckle construction comprising a pivotable slide through which a strap end may be passed, means for attaching the slide to a second strap end for pivotal movement with respect thereto, and a tongue pivotally mounted 40 on the second strap end to engage with the top of the pivotable slide, said pivotable slide having a top recess extending a substantial distance thereover for receiving the free end of the tongue to retain the same against lateral displacement, 45 said slide and said tongue being pivotable about different axes, said slide having a notch in the edge thereof facing said tongue and at the end of the top recess, said tongue having a vertical portion and a horizontal free end portion in continuation of the vertical portion, said vertical portion of the tongue passing through the one strap end and lying within the notch of the slide and within the confines of the edge of the slide and the horizontal portion lying in the top recess.

50 2. A buckle construction comprising a pivotable slide through which a strap end may be passed, means for attaching the slide to a second strap end for pivotal movement with respect thereto, 55 and a tongue adapted to enter openings in the first strap end and pivotally mounted on the strap to engage with the top of the pivotable slide, said pivotable slide having a top recess for receiving the free end of the tongue to retain the same against lateral displacement, said pivotable slide having a notch in the edge thereof aligned with the top recess to receive the end of the tongue when the slide is pivoted and to retain the tongue against lateral displacement, 60 said attaching means for the slide having a stop for limiting the turning movement of the slide and to prevent thereby the tongue from passing to the opposite side of the slide.

70 3. A buckle construction comprising a U-shaped member adapted to be secured to the end of a

strap, a pivotal slide having top and depending side portions and means for pivotally connecting the side portions to the ends of the legs of the U-shaped member for pivotal adjustment whereby the buckle may adapt itself to the strap which may be pulled through the same, and a tongue pivotally connected to the U-shaped member and adapted to engage with the top of the pivotal slide, the legs having flat end surfaces engageable by the slide top portion to limit the pivotal movement of the slide and to prevent the passing through of the tongue from one side of the slide to the other, said slide having a notch in its edge for receiving the end of the tongue to retain the same against lateral displacement when the slide is pivoted against the flat end surfaces of the leg ends.

4. A buckle construction comprising a pivotable slide through which a strap end may be passed, means for attaching the slide to a second strap end for pivotable movement with respect thereto, and a tongue pivotally mounted on the second strap end adapted to enter openings of the first strap end and to engage with the slide, said attaching means for the slide having a stop portion thereon to limit the pivotal movement of

the slide away from the tongue and thereby to maintain control of the tongue at all times, said slide having top and depending side portions, said slide attaching means including a U-shaped member with forwardly extending legs, said slide depending side portions being pivotally connected to the ends of the legs of the U-shaped member, the pivot axis of the pivotable slide being nearer to the outer edge of the slide than to the tongue engaging edge of the slide.
